FIG. 8

FIG. 9

FIG. 1 is a three-quarter side perspective view of a luggage case showing my new design;

FIG. 2 is an end elevation of the luggage case of FIG. 1 but taken from the end opposite to that shown in FIG. 1;

FIG. 3 is a side elevation of the luggage case of FIG. 1;

FIG. 4 is a top plan view of the luggage case of FIG. 1;

FIG. 5 is a bottom plan view of the luggage case of FIG. 1;

FIG. 6 is a fragmentary side elevation similar to the lower portion of FIG. 3 but showing a variation in the appearance of the supporting feet;

FIG. 7 is a fragmentary end elevation similar to the lower portion of FIG. 2 but showing the variation in the appearance of the supporting feet, as in FIG. 6;

FIG. 8 is a perspective view, similar to FIG. 1, of the luggage case having a variation in the appearance of the supporting feet or glides, as in FIGS. 6 and 7; and

FIG. 9 is a bottom plan view, similar to FIG. 5, but showing the variation in the appearance of the supporting feet or glides, as in FIGS. 6 and 7.

The essential features of my design reside in the full line showing thereof; the broken line showing of the conventional handle and latches has been omitted in FIGS. 1 and 8, for clarity of illustration.

I claim:

The ornamental design for a luggage case, as shown and described.
